UNITED STATES PATENT OFFICE.

MILTON W. HAZELTON, OF NEW YORK, N. Y., ASSIGNOR TO HIMSELF AND
E. S. T. KENNEDY, OF SAME PLACE.

SECTIONAL STEAM-BOILER.

SPECIFICATION forming part of Letters Patent No. 247,910, dated October 4, 1881.

Application filed August 5, 1881. (No model.)

To all whom it may concern:

Be it known that I, MILTON W. HAZELTON, of the city, county, and State of New York, have invented a new and Improved Sectional 5 Steam-Boiler, of which the following is a full, clear, and exact description.

The object of this invention is to construct a boiler that shall be economical of fuel, quick to generate and superheat steam, easy of repair, 10 and occupying comparatively little ground room.

In the accompanying drawings, Figure 1 is a sectional elevation of my improved boiler set in brick-work on line *w w*, Fig. 4. Fig. 2 is a cross-section of the same on line *x x*, Fig. 1. Fig. 3 is a cross-section of the same on the line *y y*, Fig. 1. Fig. 4 is a cross-section of the same on line *z z*, Fig. 1.

Similar letters of reference indicate corresponding parts.

In the drawings, *A* represents the vertical central cylinder of the boiler, having internal stay-rods, *a a*, for supporting its heads *A' A'*. The bottom of said cylinder *A* is set on a suitable support, *B*, and around the lower end of said cylinder *A* is an annular ash-pit, *C*, above which is the fire-chamber *D*, separated from the latter by a grate, *E*, composed of perforated plates, as shown in Fig. 4. The opposite fuel-entrances into the fire-chamber *D* are represented at *b b*. From the top of the fire-chamber *D* to a point several inches below the grate *E* the cylinder *A* has an unbroken surface.

At the top of the fire-chamber *D* are two series of water-containing tubes, *F*, set conveniently close together, one above the other, radiating from the cylinder *A*; and connected with these tubes *F* by elbows *c c* are perpendicular tubes *F'*, that are extended downward 40 through notches *d* in the edge of the grate *E*, and have their lower ends connected by elbows *f* with horizontal tubes *F''*, that are entered into the cylinder *A* near its bottom; hence it will be seen that the tubes *F'* form, essentially, the inner lining of the fire-chamber *D*. Over the fuel-entrance *b b* these tubes *F'* are cut off and connected to horizontal tubes *F''*, as indicated in Figs. 1 and 4. It will be seen that by this arrangement of tubes a tubular water-jacket 45 is formed for the fire-place.

From just above the tubes *F* nearly to the water-line of the boiler the space within the boiler-inclosing walls *H* is filled with series of tubes *I*, closed at their outer ends and radiating from the cylinder *A* in successive planes 55 one above the other, the tubes and spaces of the several series alternating with each other, as shown in Fig. 3, and above the upper series of tubes *I*, below the water-line, radiate from the cylinder *A* a series of tubes, *K*, whose 60 ends are connected by elbows *g* with perpendicular tubes *K'*, that extend downward almost in contact with the boiler-walls *H* to below the tubes *F''*, and are at this point connected by elbows *h* with horizontal tubes *K''*, that are 65 entered into the cylinder *A*. By this arrangement of cylinder and tubes a maximum fire-surface is obtained in a given space, and great economies in fuel are thereby made possible.

A little above the boiler water-line, which is 70 indicated at *k*, Fig. 1, the cylinder *A* is enlarged into a steam-chamber, as shown at *A⁴*, and extending horizontally from about the bottom of this chamber *A⁴* is a perforated circular disk, *L*, while from the top thereof extends 75 another perforated circular disk, *M*.

Extending between the disks *L M*, and with their ends fitted in the perforations thereof, are vertical flues *N*, set in concentric circles about the steam-chamber *A⁴*, and serving for 80 the escape of the products of combustion from the fire-chamber *D*.

A cap, *O*, provided with a smoke-pipe, *O'*, surmounts the whole device.

The products of combustion escaping through 85 the flues *N* serve to superheat the steam in the chamber *A⁴*, and from said chamber *A⁴* the steam is conducted through pipe *P*.

Having thus described my invention, I claim as new and desire to secure by Letters Patent—

1. The combination, with a central upright cylindrical boiler, *A*, having a series of radiating tubes, *I*, closed at their outer ends and arranged in successive planes one above the other, the tubes and spaces of the several series alternating with each other, of a series of vertical tubes, *K'*, set in the spaces between the outer ends of said radiating tubes *I*, and extending from near the water-line to the bottom 90 95 100

of the central boiler, A, and communicating therewith at their ends through horizontal pipes K K², and of a series of short vertical tubes, F', and horizontal connecting-pipes F F² 5 and vertical smoke-flues N, set in concentric rings about the steam-chamber, arranged as set forth.

2. In a sectional steam-boiler, the combination, with the central vertical cylinder, A, of

the connected water-tubes F F' F² F³, radiating tubes I K K², perpendicular tubes K', disks L M, and vertical flues N, arranged substantially as herein shown and described.

MILTON W. HAZELTON.
